[57] CLAIM

The ornamental design for a telephone receiver cap for earrings, as shown and described.

DESCRIPTION

FIG. 1 is a front elevational view of the telephone receiver cap for earrings showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective full line view of the ear piece shown in FIG. 1 depicted in the environmental association of a broken line handset, and broken mouth end round apertures therein.

The broken line showing of a telephone handset and broken line showing of apertures in the mouth end of the handset is for illustrative purposes only and forms no part of the claimed design.
